UNITED STATES PATENT OFFICE.

JOHN D. WEBBER, OF BAYONNE, NEW JERSEY.

LAYING-OUT DEVICE.

1,237,001.

Specification of Letters Patent. Patented Aug. 14, 1917.

Application filed December 26, 1914. Serial No. 879,160.

To all whom it may concern:

Be it known that I, JOHN D. WEBBER, a citizen of the United States, and resident of the city of Bayonne, in the county of Hudson and State of New Jersey, have invented certain new and useful Improvements in Laying-Out Devices, of which the following is a specification.

This invention relates to a device for laying or marking out work which is afterward to be machined or done manually.

The primary object of the invention is the production of a device which will dispense with the tedious method usually followed in a machine shop for laying out a piece of work, prior to its being drilled, or otherwise dressed. In preparing a piece of work, it has heretofore been the practice of fastening the same to a stationary angle plate, lining up both extremities thereof so that surfaces and holes to be finished come into substantial alinement, scribing one or more parallel lines thereon, then loosening the piece, resetting and reclamping it in a changed position, for scribing other lines intersecting the first. All of these steps consumed a great deal of time, and if the weight of the work was of any magnitude it also imposed further labor in holding it while being transferred from one position to another. Mistakes were liable to happen if the operator did not exercise more than ordinary care in preventing the work or piece from shifting on the angle plate, particularly, if the scribed lines converged in certain angular relations to one another and had to be laid out by means of an angle protractor. Errors frequently occurred, if the said lines extended at some appreciable distance from the protractor instrument.

A secondary object is to provide an implement for the purposes set forth, which will save time, by facilitating the rapid setting up of a piece of work such as a casting or forging and changing it from one position to another incidental to scribing parallel and intersecting lines as well as affixing other marks thereon, for the guidance of an artisan in performing the necessary mechanical operations.

A further object is to produce a device of the character described which shall be of simple and rigid construction as well as comparatively inexpensive, thereby enabling the smaller shops to possess the same and lessening the labor connected with odd or

special pieces of work of which there may not be enough to warrant the investment of jigs or similar fixtures.

Another object is the provision of a device wherein all operating parts are accessible for convenient manipulation and exposed to view so as to permit accurate and first-class work to be done expeditiously at low cost.

Further objects and advantages will become apparent as the specification proceeds.

With the aforesaid objects and advantages in view the invention consists in the improvements and combinations of parts hereinafter described in their preferred embodiments, pointed out in the subjoined claims, and illustrated on the annexed drawings, in which:

Figure 1 shows a front view of the invention;

Fig. 2 is a transverse section taken on the line 2—2 of Fig. 5, in the direction of the arrows;

Fig. 3 is a like view taken on the line 3—3, in the direction of the arrows, parts 80 being omitted;

Fig. 4 is a view similar to Fig. 1, with an element in a changed position;

Fig. 5 is a longitudinal section of the previous figure taken on the line 5—5 in the direction of the arrows;

Fig. 6 is an enlarged partial plan view of a degree scale and coacting vernier, used in conjunction with the device; and

Fig. 7 is a similar view of a modified form of the scale and vernier.

In these views the numeral "11" denotes a base from which extend uprights 12, 13, and the latter as well as said base may be hollow as shown. In the preferred construction, these uprights are set back inwardly from the front and rear edges of the base, being connected therewith by inclined walls which form an open space or clearance outside of the said uprights, the purpose whereof will be more fully hereinafter referred to. The longitudinal sides of the said base project outwardly of the uprights and afford ledges 18, 19 adapted to receive the ends of clamps (not shown) by means of which the base can be held to a primary support, such as a surface plate for instance. To this end the underside of the base 11 is machined or finished to a plane and even bearing surface. On the inside, the said base may be provided with ribs 21, 22 spaced a certain distance away from and parallel with the

longitudinal walls thereof. Paired slotted openings 23, 24 are disposed through the tops of the ledges 18 and 19 outside of the uprights between the said walls and ribs 21, 5 22, which slots are designed to take over the ends of bolts (not shown) entering the primary support, where the construction admits of using such fastening means.

At their upper ends the uprights 12, 13 10 are provided with bearings 29, 30 in which is journaled a spindle 31. A forwardly extended portion 32 of the front bearing 29 is concentrically arranged with regard to the spindle journal and constitutes the inside bearing surface of sleeves 33, 34 rotatably mounted one after the other upon said surface. At the outer end of said spindle is fastened or formed integral therewith a work carrier or holder 35 which in the 15 present exemplification consists of a face plate located right angularly with relation to the axis of the spindle. The inner end 36 of the said carrier plate is shouldered and abuts against the outside portion 32 of the bearing 29, and a collar 37 fixed to the rear 20 of the spindle 31 adjacent the bearing 30 maintains the said spindle and the therewith rotatable carrier 35 in axial alinement. Various means may be employed for holding a 25 piece of work such as a casting, forging or other object to the carrier 35. The instrumentalities shown consist of groups of elongated apertures 38 radially disposed at different distances from the center of the 30 spindle 31, which latter, if preferred, may be made hollow. A clamp strap or bridge 39 is pulled up against and holds the work to the face plate 35, as for instance, by means of a bolt 40 passing through one of the 35 apertures 38, with its head bearing on the inner side of the said face plate. To give the latter sufficient rigidity an annular flange 41 is formed circumferentially therearound, which flange is provided with graduations 42 in the arc of a circle.

An index arm 47 forming part of the outer sleeve 33, that is loosely mounted on the bearing extension 32, coacts at its outer end 48 with the graduations 42 on the periphery 50 of the work carrier which it overlies. The said end 48 is broadened in the nature of a vernier with graduations 49 thereon. Two exemplifications of coacting circular scales and verniers are shown in Figs. 6 and 7. In 55 the former figure, is illustrated how the graduations on the edge of the carrier 35 denote every degree of the circle, while the distance of five degrees on the vernier is divided into six equal parts of 10 minutes between each. In other words, each of said parts is equal to one degree less one sixth thereof. Thus for example, if the one degree mark, below the zero on the scale, be moved to the ten mark, that is between 0 and 60 20 on the vernier, the carrier has been given

an angular adjustment of 10 minutes. Likewise, if the second degree mark on the scale be moved to the twenty minute division on the vernier the adjustment is 20 min.; 3rd mark to 30=30 min.; 4th to 40=40 min.; 5th to 50=50 min.; and obviously, if the sixth degree mark on the scale is moved to the 60 division on the vernier, 60 minutes or a full degree is registered. Where the character of the work is such that it does 75 not require the accuracy attainable with the aforesaid arrangement, it may suffice to mark the carrier edge with only a scale of every fifth degree as represented in Fig. 7 and to divide the same distance on the vernier in five equal parts of one degree each. Whereof follows, that every advance of a graduation on the scale to one of the vernier, produces an adjustment of one degree, and the fractions of a degree, such as $\frac{1}{4}$, $\frac{1}{2}$ and so 80 on, are left to the operator's estimation or judgment in setting the carrier or face plate.

The index arm 47 is held in a predetermined position on the bearing extension 32 by means of the before mentioned sleeve 34, the hub of which is split and clamped to the said extension by a bolt 50. One end of the latter is threaded into one of a pair of ears 51, provided on the said split sleeve 34, and bears with its shoulder 52 against the other ear thereof, while a comparatively long shank 53 of the bolt projects with its operating head 54 sufficiently outward to afford a convenient manipulating grip. A pair of arms 55, 56 spaced in parallelism apart extend out from the sleeve hub 34 substantially opposite to the clamping means thereof. A headed screw 57 having threaded engagement with the outer end of the arm 55 bears with its other end against an ear 58 rearwardly offset from the index arm 47. By the adjustment of this screw the graduations on the vernier head 42 of the said arm 47 may be brought in register with the graduations on the circumferential edge of the carrier plate 35. Although the means for holding the arm 47 up against the adjusting screw 57 has been shown as consisting of a similar screw 59 threaded into the corresponding arm 56 it is understood that 115 any other element accomplishing the same purpose could be used as well.

To hold the spindle 31 and the therewith connected work carrying plate 35 fixedly in their assigned position, a split hub 64 is arranged to grip around the said spindle. As represented, this latter clamping hub is placed adjacent to the inner face of the front bearing 29, but it is obvious that it could be located elsewhere on the spindle. 120 A bolt 65 with a handle portion 66 within convenient reach of the operator, has its threaded end engaging one of a pair of ears 67 projecting from the top of the said hub. Substantially diametrically opposite these 125 68

ears extends an arm 69, having its inner portion 70 widened and slotted to afford increased resiliency to the said hub 64 when the clamp screw 65 is tightened. The outer 5 end of the arm 69 is received between the inner ends of adjusting screws 71, 72. In Figs. 3 and 5 is represented how these screws have threaded engagement with lugs 73, 74 respectively, formed with the inner surface 10 of the front upright 12, but it is readily perceived that the said screws can be operatively maintained in any other part of the structure.

At the rear end the said spindle 31 is provided with screw threads 75 adapted to receive the threaded hub of a chuck, such as 15 is used for example on a lathe. Here, the edge of the face plate fills the function of a graduated dial.

The operation of the device is more readily understood in conjunction with the description of how a certain piece of work, for instance, an angle or bell crank lever A, shown by dotted lines in Figs. 1 and 4, is 20 laid out. The apparatus in its entirety is placed on and secured to a surface plate, which may be either of the bench or floor variety depending upon the size of the work to be handled. The operator, first, clamps 25 and locks the spindle 31 with the work carrier 35 firmly in position by means of the bolt 65 and adjusting screws 71, 72. Secondly, he fastens the work, to the face of the carrying plate 35 as by means of a strap and 30 bolt, as shown. After having chalked or otherwise prepared the surface of the bosses b, c and d of the lever A, he places a surface gage preferably on the same surface plate upon which the base of the device 35 stands, and adjusts the scratching point of 40 the gage until it comes approximately even with the center of the bosses b and c. If the latter should happen to be out of level which is usually the case at first, the operator 45 can easily rectify this, by loosening one and tightening the other, of the before mentioned adjusting screws 71, 72, until the correct alinement is secured. Thirdly, after he has located these bosses and the scratching 50 point of the gage in correct location one relatively to the other, the operator proceeds to scribe a line e on the said bosses. Fourthly, he measures on a scale or rule the distance at which the center of the upper 55 boss d should be placed from the line e, sets the scratching point of the surface gage to this dimension, and lays off or scribes the upper line f parallel to e. Fifthly, the operator locates the vernier head 48 in register 60 with some certain graduation on the circular scale 42 of the work carrier, it not being necessary to select zero every time, since any given graduation may be chosen to start from. This adjustment is first tried roughly 65 by fixing the sleeve 34 by means of the clamp

bolt 50 on the bearing extension 32, the final adjustment being obtained by the screws 57, 59. If in starting, two outside or extreme lines on the vernier are made to stand in correct correlation with a pair of 70 graduations on the edge of the plate 35, it will contribute to accuracy in positioning these elements. Sixthly, the next step taken by the operator on the particular piece of work operated upon, is to turn the work carried 75 90 95 100 105 110 115 120 125 130 90° or one right angle around, this being accomplished by loosening the clamp hub 64, rotating the carrier with the work thereon the required amount, tightening the bolt 65, and effecting the final setting by 80 means of the adjustment screws 71, 72. This latter position is illustrated by Fig. 4. Seventy, the operator proceeds to lay out the cross lines g, h and i in the same manner as before described with regard to the lines e and f. The work piece is next removed from the carrier, and the intersections between the various lines marked with a prick punch. The work is now ready to be placed under the drill press to have the desired size of holes bored therein and the bosses faced if necessary. Should it be required to lay out other angles besides the one mentioned, it is obvious that the same procedure is followed, and if it should be found necessary to lay out different angles in succession on a certain piece of work, this is readily accomplished by first moving the edge scale of the carrier to the vernier, next, changing the vernier to the new angle, then the carrier 100 to the new angle also, and so on, until all the angles one after the other have been laid out. A different or changed position of the vernier arm 47 with its adjusting screws is indicated by dotted lines at J Fig. 2. The clearance or open space between the inwardly offset front upright 12 and the rear edge of the work carrier is especially advantageous when the index arm stands below the bearing or the sleeves, as it gives the operator free and easy access to adjust the screws 57, 59.

Although the lines laid out on the work piece illustrated in Figs. 1 and 4, extend in the same plane as the work-carrier, it is obvious that lines can be scribed perpendicularly against the latter, should the nature of the work require it. Furthermore, by guiding the surface gage on the face of the work carrier, the operator may lay out other lines intersecting those last named at a right angle.

Should the occasion require the use of a chuck at the end of the spindle 31, it is self evident that the manipulation of the device 125 is precisely the same as before, the face plate with the edge graduation thereon serving as an indexing dial.

While certain preferred embodiments of this device has been shown and described, it 130

will be understood that changes in the form, arrangement, size, proportions and details thereof, may be made without departing from the scope of the invention as defined by the appended claims.

Having described my invention what I desire to secure by Letters Patent and claim is:—

1. A laying-out device, comprising a rotatable carrier adapted to retain work relatively fixed thereon, means for holding said carrier with the work in a predetermined position, and means for subsequently adjusting said holding means.
2. A laying-out device, comprising a revoluble carrier arranged to hold work at right angles to the axis of rotation, indexing means coacting with said carrier, and other means coaxial with said indexing means and the carrier for clamping the latter with the work and adjustable angularly relatively to the first mentioned means.
3. A laying-out device, comprising a rotatable carrier adapted to hold work in a predetermined position, indexing means coöperating with said carrier and adjustable independently thereof, and other means for clamping the work holding carrier, said other means being capable of adjustment together with the latter relatively to said indexing means and also apart from the said carrier.
4. A laying-out device, comprising a revoluble carrier bearing graduations and adapted to retain work relatively fixed thereon, indexing means rotatively adjustable with relation to said graduations, and means for clamping the work holding carrier in a predetermined position independently of said indexing means.
5. A laying-out device, comprising a rotatable carrier adapted to hold work in a relatively fixed position, said carrier having peripheral graduations, an index mounted concentrically with the axis of said carrier co-operating with the graduations on the latter, means for adjusting said index, clamping means for holding the carrier independently of the index, and other means for setting the carrier with relation to the index.
6. A laying-out device, comprising a rotatable work carrier having circumferential graduations, a rotatably adjustable arm extending radially of the axis of said carrier, and a vernier projecting from said arm over said graduations.
7. A laying-out device, comprising a rotatable work carrier with graduations on the periphery thereof, a radial arm revolvably mounted in rear of said carrier, a vernier on said arm overlying the periphery of the carrier co-acting with the graduations thereon, and means for adjusting the arm with the vernier independently of the said carrier.
8. A laying-out device, comprising a rev-

oluble work carrier, a clamping arm coaxial with said carrier and rotatable independently thereof coöperating with the carrier, an index arm coöperating with the carrier mounted loosely with relation to the latter to register its setting, and means for adjusting said arms relatively to each other.

9. A laying-out device, comprising a revoluble work carrier, an arm capable of being clamped concentrically with said carrier at a predetermined part thereof, an index arm located adjacent said first named arm and adapted to register the setting of the carrier, means for adjusting said index arm with relation to the other arm, and other means for holding the index arm against said adjusting means.

10. A laying-out device, comprising a rotatable work carrier, a sleeve mounted loosely around the axis thereof, an index arm extending from said sleeve to the periphery of said carrier in position to indicate various settings thereof, a clamping sleeve adjacent to said first named sleeve and capable of adjustment independently of the carrier, an arm projecting from said clamping sleeve in proximity to said index arm, and interconnecting means whereby the index arm may be set with relation to the clamping arm.

11. A laying-out device, comprising a rotatable work carrier, means for holding said carrier in a relatively fixed position, and other means for adjusting said holding means and thereby securing further adjustment for the carrier in the same plane.

12. A laying-out device, comprising a rotatable work carrier, means for holding said carrier in a relatively fixed position, and other means for imparting additional angular adjustment to the carrier in the same plane of rotation.

13. A laying-out device, comprising a rotatable work carrier, a support therefor, means for gripping said carrier, and other means for adjusting said gripping means relatively to said support to effect additional adjustment of the carrier in the same plane.

14. A laying-out device, comprising a rotatable work carrier, a support therefor, means for holding said carrier in a predetermined plane, and other means connected with said support adapted to act upon said holding means to effect further adjustment of the carrier in the said plane.

15. A laying-out device, comprising a rotatable work carrier, a support for the same, retaining means for said carrier, and other means including parts acting in opposition to each other whereby adjustment of said retaining means and the carrier is effected.

16. A laying-out device, comprising a rotatable work carrier, a support for said carrier, clamping means for holding the latter relatively fixed, an arm extending from said clamping means, and other means with said

support acting upon said arm for effecting angular adjustment of the carrier in its original plane of rotation.

17. A laying-out device, comprising a rotatable work carrier, a support therefor, clamping means for holding said carrier relatively fixed, an arm depending from said clamping means, and other means carried by said support acting on opposite sides of said arm so as to effect rotary adjustment of the carrier with relation to its said support.

18. A laying-out device, comprising a rotatable work carrier, a shank fastened to the latter at one end and having receiving means for an additional carrier at the other end, a support wherein said shank is journaled, and means for holding and effecting adjustment of the shank and therewith connected elements.

19. A laying-out device, comprising a rotatable work carrier having a shank, a support for the latter, means for holding said shank against axial displacement, and combined clamping and adjusting means located within said support operating on said carrier and shank.

20. A laying-out device, comprising a rotatable work carrier having a spindle, a support with bearings for said spindle, one of said bearings having an extension, an index adapted to indicate the setting of said carrier and capable of being rotatably held in various adjustments in said extension, and combined means for clamping and angularly adjusting the spindle and carrier.

21. A laying-out device, comprising a support, a work carrier provided with circumferential graduations and having a shank journaled in said support, one end of said shank extending beyond the bearing thereof, an index coacting with said graduations, means for holding said carrier in relatively fixed position and capable of subsequent adjustment therewith, and means for attaching a secondary carrier to the extended end of the shank enabling the former to partake of said adjustment in conformity with the indexing of the first named carrier.

22. A laying-out device, comprising a support, a spindle journaled therein, a face plate at one end of said spindle provided with graduations, the other end of the spindle being threaded to receive a work hold-

ing element, means for maintaining said spindle in a relatively fixed position and capable of subsequent adjustment therewith, and an index coöperating with said graduations available to locate work held by said element.

23. A laying-out device, comprising a support including a bearing provided with a concentric outer portion, a graduated face plate having a spindle journaled in said bearing, a loose sleeve and a clamp sleeve rotatably mounted on said concentric portion, an index on said loose sleeve adapted to coact with the graduations of said plate, arms extending from said clamp sleeve on opposite sides of said index, and screws threaded into said arms in position to effect adjustment of the index with relation to said graduations.

24. A laying-out device comprising a support including a bearing, a graduated face plate having a spindle journaled in the latter, an index mounted on said support and adapted to coact with the graduations on said plate, a split hub around said spindle arranged to grip the same by clamping, an arm projecting from said hub, and screws threaded into the support on opposite sides of said arm in position to effect adjustment of said spindle and face plate.

25. A laying-out device comprising a support, a graduated face plate having a spindle journaled in said support, a plurality of sleeves disposed one after another along said spindle, a pair of said sleeves being rotatably sustained concentrically with the spindle, the first one in the pair including an index adapted to coact with the graduations on said plate, and the other sleeve in said pair controlling the adjustment of the first, a third sleeve mounted directly on the spindle and capable of holding it by clamping, and means for effecting angular variation of said third sleeve whereby a similar interrelative movement is produced between the graduations on the face plate and said index.

Signed at the borough of Manhattan, in the county of New York and State of New York, this 23rd day of December, A. D. 1914.

JOHN D. WEBBER.
